MACHINE FOR SHOEMAKING

Louis Sabo, New York, N. Y., assignor to Herman B. Delman, New York, N. Y.

Application April 9, 1940, Serial No. 328,772

17 Claims. (Cl. 12—17)

My invention relates to the art of shoemaking.

The object of my invention is to provide a machine by means of which women's shoes may be made at a lower cost, and is directed to the forming of the breast flap for covering the breast of a heel, the object being to provide means for forming such a flap integral with the sole and shaped to conform in height and contour with a heel of selected pattern, and which may be easily set or adjusted to cause the flap, when made, to accurately fit the breast of the heel selected when the heel is thereafter placed in its final fixed position on the shoe.

A further object is to provide a machine for the above stated use which may be operated by unskilled persons, the machine being so constructed that when set by a skilled artisan, the person operating the machine simply places the last with the upper and sole thereon, in the machine's guiding mechanism, comprising a manually operated slide which guides the shoe and flap into a predetermined position for the forming operation, then causing the die to form the flap, and thereafter removing the last with the shoe thereon by retracting the guiding slide.

In making shoes for women, heels are used which differ in length, width and form of the breasts, and it is the general practice to make the flap of greater width than that of the breast of the heel, and after the flap has been cemented to the breast, to trim the laterally extending portions with a knife by manual operation, which requires time, and skill to prevent cutting the heel in the act of removing the trim; therefore a further object of the present invention is to provide means for overcoming the danger of injury to the heel by the trimming operation.

A pair of shoes consists of a right and a left shoe, formed to differ in pattern, thus requiring a change in the adjustment of the machine's positioning device, depending on whether a right or a left shoe sole is being operated upon to provide a properly shaped flap for same, as will be readily understood; therefore a further object of the invention is to provide a machine having definitely adjustable means for guiding and positioning the shoe and flap relative to the cutting die, to insure the perfect registration of the formed flap with the breast of the heel after the heel has been placed on the shoe in its proper predetermined position.

The present invention is directed to the further improvement in the method of and machine for making shoes shown in the patent issued to me

December 21, 1937, and bearing No. 2,103,120, in which dies used in making formed flaps for heels are described, and which die constructions may also be used in the present machine, together with parts of the device shown in said patent.

In using the machine shown in said patent, the operator was obliged to place the shoe in exactly the correct position relative to the flap-forming dies to insure a proper fit of the formed flap with the breast of the selected heel when placed in proper position on a shoe, thus requiring a highly skilled operator who was capable of judging the correct position of the blank flap prior to the forming operation, mistakes causing loss of material and time and a failure in the fitting to properly match the form of the breast of the heel resulting therefrom; such troubles being entirely eliminated by the present method and machine for the purpose designed.

20 Referring to the drawings which form a part of the specification:

Fig. 1 is an elevational perspective view of a press, and a machine embodying my invention, together with a shoe upper and sole mounted on a last, the flap portion of the sole having been formed by the die; the shoe being partly removed from the machine to disclose the relative positions of the shoe, flap and slide prior to the removal of the last.

25 Fig. 2 is a plan view of the lower die member supported on a plate mounted on vertically extending side plates of the housing, and also disclosing the slide elements of the carriage which are located below the plate which carries the forming die.

30 Fig. 3 is a longitudinal sectional view, taken on line 3—3 of Fig. 4, and showing a portion of the housing, means for limiting the movement of the carriage, and means for moving elements laterally by means of a lever operated manually in setting the machine.

35 Fig. 4 is a front elevational view showing the springs which carry the upper plate and upper die, and also shows the side walls of the housing and a lower die member supported thereby.

40 Fig. 5 is a plan view of the arms of the slide forming a part of the carriage on which the last is mounted when the machine is operated, together with means for adjusting the degree of movement of the carriage.

45 Fig. 6 is an inverted plan view of the construction shown in Fig. 5.

50 Fig. 7 is a perspective view of an abutment element which is used in positioning the last on the carriage.

Fig. 8 is an end front view of the carriage, a portion of the last being also indicated.

Fig. 9 is a sectional view along the central line of a modified form of the machine, in which a cutting die is used instead of a shearing die, and a cam and lever are embodied in the machine instead of utilizing a separate press, the last and all parts being in the position in which the flap is about to be stamped out.

In the embodiment illustrated in Figs. 1-8 of the drawings, I provide a housing, comprising a base-plate 15, side walls 21, and a top plate 22 which carries a lower die member 13 designed to form a flap when the upper die member 12 is forced into co-operative engagement therewith.

10 10 indicates the platform of a press of usual construction, provided with means (not shown) for actuating said upper die. The base-plate 15 of the housing is secured to said platform 10 in detachable relation, by the clamp construction 16 as illustrated, or in any suitable manner.

15 17 indicate vertically extending pillars secured to the base-plate 15, which support springs 18, which in turn carry a laterally extending plate 19 fixed to depending tubular guides 20 which are 25 slideable on the pillars, which extend therethru, and which plate 19 carries the upper die. As shown, the lower die is formed integral with the plate 22, but may instead be carried by said plate.

20 23 indicate two side strips which are secured to the side plates 21 by bolts 24, and 25 indicate the supporting arms of the carriage.

The carriage comprises a plate 26, secured in fixed relation with the arms 25, said plate being provided with two transversely extending slots 27 and 28, spaced from each other as shown.

25 30 A plate 35 located below the plate 26 carries a slideable element 30 guided in the slot 28, which carries an upwardly extending pintle 31 which supports the last borne by the carriage.

Carried by the plate 33 and located in the slot 27 is a laterally slideable element 32, which is also carried by the plate 35 which plate is actuated by the lever 36, which is pivoted at 37 and is slotted at its inner end, and a pin 38 extends through this slot 40 and into the element 32 in fixed relation therewith and consequently movable by the lever.

35 40 45 50 43 indicates a screw which extends through the back wall 59 of the housing and is used to adjust and limit the movement of the carriage. 44 indicates the handle of the lever 36.

One or both sides of the carriage is calibrated as illustrated at 45, to serve as a guide in adjusting the inward stroke or movement of the carriage.

46 55 60 65 70 75 48 indicate two adjusting pins, actuated by integral screws 47, for limiting the movement of the sliding element 30.

The slot 41 in plate 35, and screw 42 therein, cooperate in securing straight transverse motion of said plate and attached parts.

The sliding element 32 has two V-shaped recesses 48 in its forward face, as shown in Figs. 5 and 7. A pair of tubular openings 50 are closed at their forward ends by plate 51 and constricted at their inner ends. Each contains a spring 52, the outer ends of which bear against the plate 51 and the inner ends of which bear against members 53, the wedge-shaped ends of which are pressed partly through the constricted inner ends of tubular openings 50, for engaging the V-shaped recesses 48 of the element 32, but cannot pass entirely out. The openings are spaced further apart than the recesses 48, so that at

either extreme position of the element 32 in the slot 27 one of the springs can press its member 53 into the corresponding recess 48, the member 53 of the other tube remaining disengaged because out of register with the other recess.

34 is a positioning member, being an integral part of the plate 33 (see Figs. 5 and 7), and serves to position the forward portion of the last between itself and one or the other of the members 54, according to whether a right or left shoe is inserted in the machine. The members 54 are thin enough to yield upon movement of the abutment 34 forcing the last against the same, and are secured to the carriage plate 26.

57 are two guiding members fixed to the plate 22 near the cutting edge of the lower die, and act to bring the leather strip into laterally correct position.

This embodiment of the invention constitutes a unitary mechanism, which may be inserted in and actuated by any suitable press.

The operation of this embodiment of my invention is as follows: At the beginning of the operation, a skilled operator places in the machine a last bearing the upper and sole of one specimen of the particular type, style and size of shoe, a series of which is to be worked upon, the sole being split in the usual manner. To position the last, he draws the carriage outward by means of the handle 44, into the position shown in Fig. 3, and while the carriage is thus extended, places the last, designated 55, bottom up, with the hole 56 impaled upon the pintle 31, and the forward portion located between the positioning member 34 and one or the other of the members 54, depending on being a right or left shoe. The member 34 is adjusted for a right or left shoe by shifting the handle 44 laterally, the swinging motion of the handle 44 and lever 36 being translated into a straight transverse motion of the member 32. If necessary in order to bring the last into correct line, the rear portion is adjusted laterally by means of pins 46 and integral screws 47, which limit the lateral movement of sliding element 30. If required by the shape of the particular lasts to be used, one or more rings 58 are placed upon the pintle 31 to raise the rear portion of the last and bring the flap into approximately the same plane as the lower die member 13 and the spring-supported conforming plate 29 which lies in the plane of plate 22 until the press is actuated. The last is thus held firmly in its adjusted position upon the carriage. The screw 43 is set to limit the rearward movement of the carriage.

These adjustments being correctly made, the carriage is pushed rearwardly, to the extent permitted by the screw 43, and then occupies a position similar to that shown in the modified view Fig. 9. The flap 14 passes above and rests upon the plate 22 and lower die member 13, and is thus automatically positioned correctly, and the press is then operated, the plunger 11 depressing the plate 19 and forcing the upper die member into shearing engagement with the lower die member and cutting the desired shape of flap in exactly the desired and predetermined location.

In Fig. 3, the trim remaining from the cutting operation is indicated at 39.

The adjustments having been once correctly made, the operation may be repeated on successive shoes by an unskilled person, who can also adjust the machine from right to left or vice versa, by merely swinging the handle. When a different size or shape of last is to be worked

upon, new adjustments are made by the skilled operator, and if the flap is to be cut for a different type or height of heel, different dies are inserted.

The embodiment shown in Fig. 9 is modified in certain respects. An integral arm 65 extending from the rear wall of the machine, supports a cam 63, actuated by a handle 64, to cause the downward movement of the upper die. In this embodiment a cutting die is shown instead of a shearing die as in the embodiment first described. 61 indicates a plate upon which the flap 14 rests, this plate being supported by four cylindrical springs 62, and yielding when the die 60 cuts the flap, thus avoiding undue blunting of the die. The side walls 66 in this modification do not support the plate 61, but only act as guides to insure a straight downward movement of the plate.

Other parts of the machine are similar to the mechanism carried by the housing of the embodiment first described, and the operation of the modified embodiment will therefore be clear from the drawings and from what has been already said.

The advantages of the invention will be obvious from what has been above said with regard to the objects, construction and operation of the invention.

I do not limit myself to the particular details of construction and operation which have been described in this specification and illustrated in the drawings, as it is obvious that various modifications may be made in the same, within the scope of the claims hereof, without departing from the spirit and scope of the invention.

Having thus described my invention, what I claim as new and desire to secure by Letters Patent is as follows:

1. A machine of the character described, comprising supporting and guiding means for a carriage, a carriage guided by said guiding means, means on said carriage for supporting the heel portion of a last having a shoe thereon provided with a blank flap portion for covering the breast of a heel, laterally adjustable means acting upon a relatively forward portion of said last for holding said portion in an adjusted position on the carriage, means for supporting the flap, and means operative to provide a formed flap from the blank.

2. A machine of the character described, comprising supporting and guiding means for a carriage, a carriage guided by said guiding means, means on said carriage for supporting the heel portion of a last having a shoe thereon provided with a blank flap portion for covering the breast of a heel, laterally adjustable means acting upon a relatively forward portion of said last for holding said portion in an adjusted position on the carriage, a platen for supporting the flap, and means operative to provide a formed flap from the blank.

3. A machine of the character described, comprising a housing, a carriage movable therein, guiding means for said carriage, means on said carriage for supporting a last having a shoe thereon provided with a blank flap portion for covering the breast of a heel, means for holding the heel portion of the last in an adjusted position on the carriage, laterally adjustable means acting upon a relatively forward portion of said last for holding said portion in adjusted position on the carriage, means for supporting the flap, and means operative to provide a formed flap

from the blank, said elements constituting a unitary mechanism for removable assembly with an independent operating means.

4. A machine of the character described, comprising a housing, a plate supported in the upper side thereof serving to support the heel flap of a shoe placed thereon, a flap-forming cutter located above said plate in co-operative relation therewith, a carriage designed to carry a last having a shoe thereon to a predetermined position relative to said flap-forming cutter, means for supporting and guiding the carriage to said predetermined position, means for supporting the heel portion of the last in a predetermined position on the carriage, laterally adjustable means acting upon a relatively forward portion of said last for holding said portion in adjusted position on the carriage, and means for limiting the movement of the carriage.

5. A machine of the character described, comprising a housing, a plate serving to support the heel flap of a shoe placed thereon, a flap-forming cutter, a carriage adapted to carry a last having a shoe thereon to a predetermined position relative to said flap-forming cutter, means for limiting the movement of the carriage, and means for supporting the last on the carriage, comprising laterally adjustable means for holding the heel portion of the last in a predetermined position and laterally adjustable means acting upon a relatively forward portion of the last for holding said portion in adjusted position.

6. The construction defined in claim 5, together with means for simultaneously changing the adjustment of both said last-supporting means to support a last for a right or a left shoe in adjusted position.

7. A machine of the character described, comprising a housing, means serving to support the heel flap portion of a shoe placed thereon, means operative to provide a formed flap from said blank flap, a carriage designed to carry a last having a shoe thereon to a predetermined position relative to said flap-forming means, means for supporting and guiding said flap to said predetermined position, and means for adjusting the last to and supporting the same in its final position on said carriage, comprising a plate movably secured to the body of said carriage, sliding elements carried by said plate and located in transverse slots in said main plate, a pintle carried by one of said sliding elements, an abutment carried by another of said sliding elements, and a pair of last-supporting members alternatively cooperating with said abutment.

8. The construction defined in claim 7, together with a lever for moving said movable plate and supported elements transversely relatively to the body of said carriage.

9. A construction as defined in claim 7, in which said last-supporting members are of yielding construction to hold said last between one of said members and said abutment.

10. The construction defined in claim 7, together with means for holding said secondary plate and attached parts in adjusted position, comprising a spring-actuated member engaging one of the sliding elements borne by said plate.

11. The construction defined in claim 7, together with means for holding said secondary plate and attached parts in adjusted position, comprising a pair of spring-actuated members mounted in said carriage, and a pair of differently spaced recesses in one of said sliding elements, one co-operating member and recess being disen-

gaged when the other co-operating member and recess are engaged.

12. The construction defined in claim 7, together with means for adjustably limiting the lateral movement of the sliding element bearing the pintle.

13. The construction defined in claim 7, together with adjustable pins for limiting the lateral movement in its slot of the sliding element bearing said pintle.

14. The construction defined in claim 7, together with an inclined surface adjacent said pintle upon which a portion of the last may rest.

15. The construction defined in claim 7, together with means for adjusting a portion of said last vertically to cause said heel flap to lie in approximately the plane of said flap-supporting means, comprising a ring member on said pintle.

16. A machine of the character described, com-

prising a housing, means serving to support the heel flap of a shoe placed thereon, flap-forming means, a carriage adapted to carry a last having a shoe thereon to a predetermined position relative to said flap-forming means, means for limiting the movement of the carriage, and means for supporting the last on the carriage, comprising laterally adjustable means for holding the heel portion of the last in a predetermined position and laterally adjustable means acting upon a relatively forward portion of the last for holding said portion in adjusted position.

17. The construction defined in claim 16, together with means for simultaneously changing the adjustment of both said last-supporting means to support a last for a right or a left shoe in adjusted position.

LOUIS SABO.
